Patented Feb. 13, 1917.

UNITED STATES PATENT OFFICE.

RICHARD CARR NORMAN, JR., OF GRAYTON, MARYLAND.

CARBURETER.

1,216,158.

Specification of Letters Patent. Patented Feb. 13, 1917.

Application filed July 6, 1915. Serial No. 38,146.

To all whom it may concern:

Be it known that I, RICHARD CARR NORMAN, Jr., a citizen of the United States, residing at Grayton, in the county of Charles 5 and State of Maryland, have invented certain new and useful Improvements in Carbureters, of which the following is a specification.

Gasolene or internal combustion engines, 10 utilizing volatile liquid fuel mixed with air, generally embody a carbureter through which the air is drawn by the suction of the engine and impregnated with the fuel in a vaporized state to form the gaseous 15 mixture which when ignited in the cylinder expands and drives the piston therein. It is necessary, by reason of changes in atmospheric and load conditions, that the proportions of air and vaporized fuel be varied 20 in order that the best results may be attained in securing a maximum amount of power from a given quantity of fuel and to obviate the fouling of the engine by deposition of carbon.

25 The present invention provides a carbureter which admits of the proportions of air and vaporized fuel being readily controlled either by hand or automatically, or both, and which is simple in construction and embodies 30 a few number of parts, thereby being adapted for motor vehicle because of its flexibility and the ease with which access may be had to every part for any purpose whatsoever.

35 The invention consists of a carbureter having an air tube into which the gaseous mixture is injected and attenuated by further admixture therewith of air in regulated quantity as occasion may require.

40 The invention further consists of a carbureter having a valve-controlled fuel inlet, the valve having a float adjustably connected therewith and formed with a duct through which the gaseous mixture passes 45 to the air tube, and the body or bowl of the carbureter having air inlets through which the air is drawn by the suction of the engine and caused to pass through the duct of the valve along with a certain proportion of the 50 volatile liquid fuel, the mixture being delivered into the air tube in which thorough carbureting is effected.

55 With these and other objects in view, which will readily appear as the nature of the invention is better understood, the same consists in the improved construction and

novel arrangement and combination of parts which will be hereinafter fully described and particularly claimed.

In the accompanying drawing has been 60 illustrated a simple and preferred form of the invention, it being, however, understood that no limitation is necessarily made to the precise structural details therein exhibited, but that changes, alterations and modifications 65 within the scope of the invention as claimed may be resorted to when desired.

The drawing is a vertical central section of a carbureter embodying the invention.

Corresponding and like parts are referred 70 to in the following description and indicated in both views of the drawings by the same reference characters.

The carbureter comprises a bowl, or hollow body 1, which may be of any material 75 although glass is preferred as it enables the interior to be observed at all times, thereby avoiding the necessity for removing the cover to inspect the float, valve and other parts. A cover 2 closes the upper end of the 80 bowl or body 1 and may be secured thereto in any manner. A plurality of openings 3 are formed in the cover 2 and constitute air inlets. The central portion of the cover 2 is raised and formed with an opening 4 85 through which the upper end of a valve 5 passes. An air tube 6 is preferably formed with the cover 2 as a part thereof, although said air tube may be connected with the cover 2 in any manner so as to be supported 90 thereby. The air tube 6 is formed in its lower portion with a depression 7 which is in line with the raised portion 8 of the cover 2. The wall separating the depression 7 from the raised portion 8 is common to the 95 tube 6 and cover 2 and has the opening 4 formed therein. One end of the air tube 6 is adapted to be connected in any manner to the engine to be supplied with a gaseous mixture. The opposite end of the air tube 6 100 is provided with a valve controlled air inlet by means of which the supply of air for attenuating the gaseous mixture is supplied. A cap 9 is fitted to one end of the tube 6 and is formed with a plurality of openings 10. A valve 11 is pivotally connected to the cap 9 and is formed with openings 12 in position and number to register with the openings 10. The valve 11 is adapted to be moved to uncover the openings 10 to a 110 greater or less extent to regulate the supply of air to be added to the gaseous mixture in

the tube 6 preliminary to the entrance of the mixture into the cylinder of the engine. The valve 11 may be operated in any manner either manually or automatically.

5 A thimble 13 is fitted to the lower portion of the bowl or carbureter body 1 and is formed with an inner valve seat 14 against which the head 15 of the valve 5 is adapted to close. Nuts 16 and 17 are threaded upon 10 the thimble 13 above and below the bottom portion of the part 1 which is clamped therebetween. Gaskets 18 are interposed between the nuts 16 and 17 and the bottom portion of the part 1 clamped between such nuts so 15 as to secure a close joint and prevent injury to the body 1 when the same is formed of glass or vitreous material. The feed pipe 19 is connected to the lower end of the thimble 13 by means of a coupling 20.

20 A float 21 is mounted upon the valve 5 and is movable therewith. The float 21 may be of any formation so as to be buoyed by the volatile hydro-carbon contained in the part 1. It is preferred to construct the 25 float 21 of cork and to fit the same with a bushing 22 which is threaded to make screw thread engagement with the valve 5 so that the float may be adjusted to the proper position in order to obtain the best results possible in the carbureting of the air. A depression 23 is formed in the upper side of the float 21 at a central point and this depression constitutes a well for receiving a portion of the volatile liquid fuel which 30 passes into it through suitable passages 21' formed through the float. A bead, or flange, 24 extends inward from the inner wall of the bowl or body 1 and underlaps the outer portion of the float 21 and forms a support 35 for the float when the level of the fuel is insufficient to buoy the float. The float has a limited vertical movement between the cover 2 and the inner stop or shoulder formed by means of the bead, or flange, 24.

40 A duct 25 is formed in the upper portion 45 of the valve 5 and opens at its lower end through a side of the valve. The lower end of the duct 25 terminates in a plurality of branches 26 which curve downwardly and outwardly. The receiving ends of the branches 26 are in the same plane which preferably corresponds with the level of the volatile liquid fuel contained in the bowl or body 1. The upper end of the valve 5 is 50 made tapering and the duct 25 formed centrally in the valve extends through the apex thereof. The valve 5 is free to rise and fall with the float 21 according to the change of level of the fuel in the part 1. Normally the 55 head 15 of the valve 5 closes against the seat 14, thereby shutting off the supply of liquid fuel to the bowl or body 1 of the carbureter. When the level of the fuel lowers in the 60 part 1 the float 21 descends and the head 15 of the valve moves away from the seat 14,

thereby admitting of a supply of liquid fuel entering the bowl 1 to take the place of that consumed. As the level of the fuel rises in the part 1 the float 21 and valve 5 correspondingly move upward thereby closing 70 the head 15 against the seat 14 and shutting off the supply of liquid fuel and preventing flooding of the carbureter. The air inlets 3 are grouped about the valve 5 and incline inwardly at their lower ends, thereby directing the jets of air into the depression or well 23 with the result that a certain proportion of the liquid fuel is carried into the branches 26 along with the air thence upwardly through the duct 25 and into the 80 tube 6. The jet issuing from the duct 25 consists of air and particles of the liquid fuel and such jet expands with the result that the liquid fuel is vaporized and mixed with the air, the resultant gaseous mixture 85 being further attenuated, if necessary, by means of air entering the auxiliary air inlet represented by the openings 10. The auxiliary air travels across the jet issuing from the duct 25 and assists materially in 90 vaporizing the particles of the liquid fuel contained in the jet and in causing the production of a homogeneous gaseous mixture.

The exact level of the gasoline in the chamber 23 with respect to the branch openings 26 of the passage 25 must be determined with regard to the engine with which the carbureter is employed. Some engines require a higher percentage of gasoline in the explosive mixture than others and the level 100 in this chamber will be varied to suit circumstances by proper adjustment of the float upon the valve stem. Generally speaking, the level will be somewhere across the mouths of the openings 26, being slightly 105 higher or lower according to the quantity of gasoline necessary.

From the foregoing, taken in connection with the accompanying drawings, it will be understood that the invention provides a 110 carbureter particularly adapted for use in connection with gasoline motors of automobiles because of the flexibility of the carbureter, the fewness of the parts embodied in its organization and the facility with 115 which such parts are accessible for adjustment, replacement or any other desired purpose.

Having thus described the invention, what 120 is claimed as new is:—

1. In a carbureter, a body having a fuel inlet, a valve for closing the fuel inlet and having a duct formed in its upper portion and having the lower end of the duct opening laterally through a side of the valve, and 125 a float mounted upon the valve below the receiving end of the duct formed therein.

2. In a carbureter, a body having a fuel inlet, a valve for closing the fuel inlet and having a duct formed in its upper portion 130

and having the lower end of the duct opening laterally through a side of the valve, and a float mounted upon the valve below the receiving end of the duct formed therein, 5 said float having a depression in its upper side with its bottom in a lower plane than the receiving end of the duct.

3. In a carbureter, a body having a fuel inlet, a valve for closing the fuel inlet having a duct in its upper portion terminating at its lower end in a plurality of branches which extend downward and outward through the sides of the valve, and a float mounted upon the valve and having a depression in its upper side surrounding the valve and receiving the lower end of the branches of the said duct.

4. In a carbureter, a body having a fuel inlet, a valve for controlling the fuel inlet and formed in its upper portion with a duct terminating at its lower end in a plurality of outwardly opening branches, a float mounted upon the valve and having a depression in its upper side receiving the lower ends of the branches of the duct, and means for supplying jets of air to the upper portion of the carbureter body.

5. In a carbureter, a body having a fuel inlet in its lower portion, and a plurality of air inlets in its upper portion, a valve for controlling the fuel inlet and provided with a duct in its upper portion terminating at its lower end in a plurality of outwardly opening branches, and a float mounted upon the valve and having a depression in its upper side receiving the lower ends of the branches of the said duct.

6. In a carbureter, a body having fuel and air inlets, a valve for closing the fuel inlet and having a duct in its upper portion for the passage of a mixture of air and fuel, a float mounted upon the valve, a tube receiving the jet of air and fuel from the said valve, and means for supplying air in 45 regulated quantity to the said tube.

7. In a carbureter, a body having fuel and air inlets, a tube having connection with the body and provided with an auxiliary air inlet, a valve for closing the fuel inlet and extending into the said tube and provided in its upper portion with a duct which opens

at its lower end through a side of the valve, and a float mounted upon the valve and movable therewith.

8. In a carbureter, a body having a fuel inlet and having its upper portion raised and provided with a plurality of air inlets, a tube having connection with the carbureter body and provided with an auxiliary air inlet, a valve for closing the fuel inlet and extending through the raised portion of the carbureter and entering the said tube and having a duct in its upper portion which opens at its lower end through a side of the valve, and a float mounted upon the valve and movable therewith.

9. In a carbureter, a body provided with a fuel inlet and having its upper portion centrally raised and formed with a plurality of downwardly and inwardly converged air inlets, a tube having connection with the carbureter body and provided with an auxiliary air inlet, a valve for closing the fuel inlet and having its upper portion extending into the said tube and formed with a duct which terminates at its lower end in a plurality of downwardly and outwardly opening branches, and a float mounted upon the valve and having a recess in its upper side into which the lower ends of the branches of the said duct open.

10. In a carbureter, a body having a fuel inlet in its bottom, a cover closing the upper end of the body and formed with a central raised portion having a plurality of downwardly converged air inlets, a tube provided with an auxiliary air inlet mounted upon the cover of the carbureter body and having a depression opposite and in line with the raised portion of the cover, a valve for closing the fuel inlet and extending into the said tube and passing through the depression thereof and the raised portion of the cover, said valve having a duct in its upper portion which terminates at its lower end in a plurality of downwardly and outwardly opening branches, and a float mounted upon the valve and having a depression in its upper side receiving the lower ends of the branches of the said ducts.

In testimony whereof I affix my signature.
RICHARD CARR NORMAN, JR. [L. S.]
